Attorney

UNITED STATES PATENT OFFICE.

CHARLES H. KOHLER, OF OAKDALE, NEW YORK.

WHEEL-PULLER.

1,170,281.

Specification of Letters Patent.

Patented Feb. 1, 1916.

Application filed October 12, 1915. Serial No. 55,531.

To all whom it may concern:

Be it known that I, CHARLES H. KOHLER, a citizen of the United States, residing at Oakdale, Long Island, in the county of Suffolk, State of New York, have invented 5 certain new and useful Improvements in Wheel-Pullers; and I do hereby declare the following to be a full clear, and exact description of the invention, such as will enable others skilled in the art to which it 10 appertains to make and use the same.

This invention relates to devices for removing wheels, coupling members, and other similar articles provided with hubs, from 15 their shafts; and it consists in the novel construction and combination of the parts hereinafter fully described and claimed.

In the drawings, Figure 1 is a plan view of a wheel puller constructed according to 20 this invention. Fig. 2 is a side view of the same. Fig. 3 is a plan view of one of the arms showing a modification.

A portion of a shaft 2 is shown with a coupling member or hub 3 on it. A crossbar 25 4 is provided, and 5 is a main screw which screws in a hole in the middle part of the crossbar. This screw has a point 6 for bearing against the shaft, and it has a rectangular portion 7 for a handle for operating it.

Arms 8 are pivoted to the crossbar by pins 30 9, and several pivot holes 10 are provided in the cross bar so that the pins can be set at different distances apart. The arms have hooked ends 12 for engaging with the coupling member or wheel hub. The arms have 35 also double-eyes 11 which straddle the crossbar and engage with the pivot pins, and these double-eyes are inclined inwardly and set at an angle to the main portions of the 40 arms so that the center lines of the pivot pins are substantially at the same distance apart as the points of the hooks. Lugs 15 project outwardly from the arms adjacent to the crossbar, and 16 are setting screws 45 arranged parallel to the arms.

The screws 16 engage with holes in the lugs and bear against the crossbar. The object of using the screws 16 and the inwardly inclined double-eyes is to prevent the 50 hooks of the arms from slipping when the main screw 5 is revolved to pull the coupling member or wheel hub off the shaft.

In the modification shown in Fig. 3 each arm is formed of two parts. The outer arm 55 8 is made exactly the same as hereinbefore

described but its pivot pin 9 engages with a head 17 on an extension arm 18 instead of being pivoted to the crossbar. The extension arm 18 is pivoted to the crossbar 4 by a pin 19, and it has an inwardly inclined 60 double-eye 24 and an outwardly projecting lug 25. The lug 25 has a setting screw 26 which bears against the crossbar. When the extension arms 18 are used the reach of the arms is greater, and the pivot pins 9 can be 65 set with a very fine adjustment by the screws 26 before the screws 16 are operated to adjust the position of the pulling hooks.

The parts are placed in position as shown in the drawings and the coupling member 70 or wheel hub is removed from the shaft by revolving the main screw by hand in an appropriate direction.

What I claim is:

1. In a wheel or hub puller, a crossbar, a 75 main screw engaging with the crossbar and adapted to bear against the shaft, arms provided at one end with hooks for engaging with the hub, and having at the other end double-eyes the forked portions of which 80 straddle the crossbar and are pivoted to it, said double-eyes and hooks projecting laterally on one side of the arms, and said double-eyes having lugs which project laterally from them between their forked portions and the arms and upon the other side of the arms from the hooks, and setting screws engaging with the said lugs and bearing on the crossbar.

2. In a wheel or hub puller, a crossbar, a 90 main screw engaging with the crossbar and adapted to bear against the shaft, extension arms having heads at their free ends, said extension arms having at their other ends inwardly inclined portions which are 95 pivoted to the crossbar and having also outwardly projecting lugs provided with setting screws which bear against the crossbar, and hooked arms for engaging with the hub on the shaft, said hooked arms being provided at one end with inwardly inclined portions which are pivoted to the heads of the extension arms, and having also outwardly projecting lugs provided with setting screws which bear against the said 100 heads.

In testimony whereof I have affixed my signature.

CHARLES H. KOHLER.
